Westinghouse Electric Corporation, East Pitts-
burgh, Pa., a corporation of Pennsylvania

Application November 9, 1949, Serial No. 126,329

2 Claims. (Cl. 137—656)

1

The invention relates to an admission valve for a prime mover, more particularly to the admission valve of the intermediate-pressure turbine of a turbine installation, and it has for an object to provide for limiting of the motive fluid pressure differential applied to the servo operating piston in the direction to open the admission valve when the latter is stopped in wide open position in order to limit the stresses applied to the mechanism connecting the operating piston and the admission valve.

Where the admission valve of a turbine, particularly the admission valve of an intermediate-pressure turbine of an installation, is normally wide open, if the admission valve is stopped in wide open position, unless provision is made for limiting the differential pressure applied to the operating piston of the servo, the connecting linkage between the operating piston and the admission valve must be made quite heavy or large, or an elastic link arrangement used, to avoid large stresses in the linkage due to differential pressure acting on the operating piston in a direction for opening movement of the admission valve. The present invention is concerned with a pressure limiter to limit the force applied by the operating piston and the consequent stresses imposed on the linkage connecting the piston and the admission valve.

The foregoing and other objects are effected by my invention as will be apparent from the following description and claims taken in connection with the accompanying drawings, forming a part of this application, in which:

The figure is a sectional view of apparatus incorporating the invention.

In the drawing, there is shown an intermediate-pressure turbine 10 having an admission valve 11 of the plug type. The admission valve has a stem 12 pivotally connected to the link 14, which is pivotally connected, at 15, to one end of the lever 16, fulcrumed at 17. The other end of the lever is pivotally connected, at 18, to the stem 20 of the servo operating piston 21 arranged in the cylinder 22.

The admission and exhaust of motive fluid for movement of the operating piston is secured by means of a relay piston valve 24 having lands 25, 26 and 27 controlling communication of pressure ports 28 and 29 and the exhaust or drain port 30 with passages 31 and 32 connected to the operating cylinder above and below the operating piston 21.

The relay piston valve 24 is positioned by means of a pressure-responsive piston 34, that

2

is, if the pressure-responsive piston moves, it is followed by the relay piston valve, as more particularly disclosed and claimed in the patent to Schwendner 2,224,321 granted December 10, 1940.

The pressure-responsive piston 34 is located in the cylinder 35 and it has a stem 36. The upper end of the stem 36 is connected, by the follow-up spring 37, to the follow-up lever 38 having one end connected to the fixed fulcrum 39 and having its other end pivotally connected, at 40, to the operating piston stem 20. A passage 41 provides for liquid under controlling pressure being supplied to the cylinder 35 above the piston 34.

Below the piston, the stem 36 is provided with a cup valve 42 arranged in covering relation with respect to the core drain passage 43 formed in the relay piston valve. The upper end of the relay piston valve has piston or pressure area 44 exposed to the chamber 45 into which the cup valve extends, the chamber being supplied, through an orifice 46, with liquid under pressure from a suitable source, for example, from one of the pressure ports. A spring 47 exerts upward force on the relay piston valve in opposition to fluid pressure force exerted on the piston area.

In operation, if the pressure in the controlling pressure passage 41 decreases, then, due to the upward pull exerted by the follow-up spring 37, the piston 34 moves upwardly, thereby reducing the pressure in the chamber 45, in consequence of which the spring 47 moves the relay piston valve upwardly to follow the motion of the piston 34. With the relay piston in mid-position with the lands 25 and 26 just lapping the pressure ports 28 and 29 and the land 27 just lapping the return or exhaust port, just as soon as the relay piston valve starts to move upwardly from mid-position, pressure is supplied through the passage 31 to the cylinder 22 above the piston 21 to move the latter downwardly, the oil below the operating piston being expelled through the passage 32 which is then in communication with the exhaust or return port 30. The operating piston 21 moves downwardly to move the admission valve in an opening direction, the force of the spring 37 being reduced, whereby, with reduced controlling pressure, the relay piston valve may be restored to mid-position through the follow-up action. On the other hand, if the controlling pressure increases, the opposite operation takes place, higher pressure supplied below the operating piston moving the latter upwardly to move the admission valve in

a closing direction and increasing the force of

the spring 37 until the relay piston valve is restored to neutral position.

Because of the power required for the servomotor to operate the admission valve, with the latter wide open and stopped by the stem seal 48 constituted by engaging conical surfaces formed on the valve stem and on the valve cover, if, with the admission valve stopped in wide-open position by abutment of the stem sealing surfaces, the controlling pressure in the passage 41 changes so as to reduce the pressure supplied above the piston 34, then the differential liquid pressure acting on the piston 21 in a valve-opening direction may exert very high stresses in the linkage mechanism connecting the operating piston and the admission valve, such stresses necessitating either an elastic link construction or linkage which is quite cumbersome and heavy. The present invention involves the provision of means which operates to limit the differential pressure applied to the operating piston with the result that the stresses applied to the linkage are limited, in consequence of which the linkage may be of relatively light and simple construction.

The pressure limiter comprises a passage 50 communicating with the operating cylinder 22 above the operating piston and a passage 51 communicating with such cylinder below the piston. The passages 50 and 51 are connected to the cylinder 52 above and below the pressure-limiting piston 53. A spring 54 exerts upward force on the piston 53. The piston has a stem 55 whose lower end is provided with a cup valve 56 arranged in the exhaust chamber 57 with which communicates the pressure port 58 whose discharge end is covered by the cup valve 56. The port 58 is supplied with liquid under pressure through an orifice 59 from any suitable source. A passage 60 connects the pressure port 58 to the controlling pressure passage 41.

The passage 60 has a check valve 61 opening toward the passage 41 so that, as long as the controlling pressure is higher than the variable pressure in the passage 60, the valve 61 closes preventing any back flow of controlling pressure through the passage 60. Similarly, the controlling pressure passage 41 has a check valve 62 arranged at the upstream side of the junction of the variable pressure passage 60 therewith, the check valve 62 closing in the event of the pressure in the passage 60 being higher than the controlling pressure, whereupon the variable pressure supersedes the controlling pressure and exerts downward force on the piston 34 for movement of the relay piston valve downwardly to connect the space above the operating piston with the exhaust or return, whereby the pressure attainable above the operating piston with the admission valve stopped in wide-open position is limited.

In operation of the pressure limiter, let it be assumed that a reduction in regulated oil pressure in passage 41 has permitted spring 37 to raise piston 34 and cup valve 42, and that spring 47 has moved the relay piston valve 24 upwardly, to effect supply of fluid under pressure to the portion of cylinder 22 above the piston 21, and consequently to cylinder 52 above piston 53, while releasing fluid from the space below piston 21 and likewise from the space below piston 53. Let it further be assumed that the piston 21 is thus positioned, as shown in the drawing, with valve 11 open and the stem seal 48 thereof seated. The same differential in pressures above and below piston 21 thus exists above and below the piston.

53. If this pressure differential exceeds a predetermined value, the piston 53 forces the cup valve 56 downwardly to further limit escape of high pressure oil from the pressure port 58 until sufficient back pressure is developed therein, and consequently in passages 60 and 41, to override and supersede the main controlling pressure in the control of downward force on piston 34. With the downward pressure on the latter thus increased, the relay piston valve 24 will be moved downwardly to effect sufficient reduction in the pressure above piston 21 to lessen the valve opening force applied thereby through the medium of the members 20, 16, 14 and 12 to the valve 11, after which the relay piston valve will again be returned to lap position, as already explained.

20 The pressure limiter just described is operated to limit the differential pressure of motive fluid acting on the operating piston 21 with the admission valve stopped in wide-open position, therefore, serves to limit the stresses to which the connecting linkage between the operating piston and the admission valve is subjected, in 25 consequence of which the construction of such linkage may be relatively light and simple.

While I have shown my invention in but one form, it will be obvious to those skilled in the art that it is not so limited, but is susceptible of various changes and modifications without departing from the spirit thereof.

What I claim is:

1. The combination, with a prime mover motive fluid admission valve having a stop limiting its wide open position and a servo-motor having its operating piston connected through lever and link mechanism to the admission valve, said servo-motor including a relay movable in response to controlling pressure supplied by a passage such that a decrease in controlling pressure results in movement of the relay for movement of the operating piston to open the admission valve, of apparatus effective, with the admission valve stopped in wide open position, to limit the motive fluid pressure differential applied to the operating piston, in the admission valve opening direction, to limit the stresses applied by the latter to the lever and link mechanism; said apparatus comprising variable pressure developing means including an element disposed in flow restricting relation with a fluid escape port to establish a variable pressure, a passage including a check valve for supplying liquid under such variable pressure from the variable pressure developing means to the controlling pressure passage when such variable pressure is higher than the controlling pressure, said variable pressure developing means further including a pressure-limiting piston operatively connected to said element and a spring, said pressure-limiting piston being operable to exert force on said element in a direction to effect an increase in such variable pressure, and said spring exerting force on the pressure-limiting piston in the opposite direction to reduce the variable pressure, and passages for applying the pressures present at opposite sides of the operating piston, respectively, to opposite sides of the pressure-limiting piston, one of the last-named passages being arranged to transmit the pressure urging said operating piston in the valve opening direction to said pressure limiting piston in opposition to the force of said spring, whereby, when the pressure differential applied to the operating piston to open the admission valve

exceeds a predetermined value, with the admission valve stopped in wide open position, the pressure-limiting piston is moved thereby against the force of the spring to increase the pressure developed by the variable pressure developing means to exceed the controlling pressure and act on the relay to move the latter in a direction to reduce the pressure differential applied to the operating piston.

2. In a prime mover control equipment including a motive fluid admission valve, a stop engageable thereby upon movement to a wide open position, a servo-motor comprising a cylinder, an operating piston mounted therein and connected through a lever and link mechanism to said valve, said operating piston being operative by pressure of fluid supplied to said cylinder for opening said valve, a relay mechanism subject to pressure of fluid in a control chamber for controlling the supply and release of fluid under pressure to and from said cylinder, said relay being responsive to a reduction in the pressure of fluid in said control chamber for effecting an increase in pressure of fluid in said cylinder resulting in closing movement of said valve, and a main controlling pressure passage communicating with said control chamber for normally supplying fluid under a controlling pressure thereto, the combination therewith of pressure limiter means for limiting the force applied to said valve in the opening direction, com-

10

prising casing structure forming a second cylinder, a conduit connecting said second cylinder with the first-named cylinder, a pressure fluid escape passage formed in said casing structure, a source of high pressure fluid communicating with said escape passage, a pressure developing element mounted in said casing structure in flow restricting relation between said source of high pressure fluid and said fluid escape passage for establishing a variable back pressure, a movable abutment mounted in said second cylinder and connected to said element for operation thereof to effect an increase in such back pressure upon an increase in pressure of fluid in said second cylinder incident to operation of said operating piston to open said admission valve, a spring engaging said movable abutment for biasing said pressure developing element in the back pressure reducing direction, and a communication connected to said source of high pressure fluid and including a check valve for supplying fluid under such back pressure to said main controlling pressure passage and consequently to said control chamber when such back pressure exceeds the pressure of fluid normally supplied to the control chamber from said main controlling pressure passage.
